DESIGN.

A. F. JACKSON.

BACK OF BRUSHES, MIRRORS, &c.

No. 20,429.

Patented Dec. 23, 1890.

UNITED STATES PATENT OFFICE.

AUSTIN F. JACKSON, OF TAUNTON, MASSACHUSETTS, ASSIGNOR TO THE
REED & BARTON CORPORATION, OF SAME PLACE.

DESIGN FOR BACKS OF BRUSHES, MIRRORS, &c.

SPECIFICATION forming part of Design No. 20,429, dated December 23, 1890.

Application filed November 17, 1890. Serial No. 371,745. Term of patent 7 years.

To all whom it may concern:

Be it known that I, AUSTIN F. JACKSON, a citizen of the United States, residing at Taunton, in the county of Bristol and State of Massachusetts, have invented and produced a new and original Design for Backs of Brushes, Mirrors, &c., of which the following is a specification, reference being had to the accompanying illustration, forming part thereof.

10 The figure is a photographic illustration of the back of a hair-brush or hand-mirror embodying my design.

My design for the back of a hair-brush or hand-mirror consists of a generally paddle-shaped outline, with the sides *a a* of the wide portion fashioned into a roll of the contour of a cross-bow and with the top formed into a

somewhat similar roll *b*. The central panel formed within these border-lines is ornamented with a thickly-matted mass of flowers 20 and leaves *c*. The handle has its sides formed with reversed curved lines and has inwardly-projecting curved bulbous ornaments *d*.

The leading feature of my design is the thickly-matted mass of flowers and leaves *c*, 25 with the marginal rolls *a* and *b*, the handle portion being subordinate and non-essential.

What I claim is—

The design for the backs of brushes, hand-mirrors, &c., as herein shown and described. 30

AUSTIN F. JACKSON.
